W. H. MINEKIME.
WATER REGULATOR.

1,267,103.

Patented May 21, 1918.

UNITED STATES PATENT OFFICE.

WILLIAM H. MINEKIME, OF WATER VALLEY, NEW YORK.

WATER-REGULATOR.

1,267,103.

Specification of Letters Patent. Patented May 21, 1918.

Application filed July 31, 1916. Serial No. 112,407.

To all whom it may concern:

Be it known that I, WILLIAM H. MINEKIME, a citizen of the United States, residing at Water Valley, in the county of Erie, 5 State of New York, have invented certain new and useful Improvements in Water-Regulators; and I do hereby declare the following to be a full, clear, and exact description of the invention, such as will enable 10 others skilled in the art to which it appertains to make and use the same.

This invention relates to water regulators of the type wherein a float is employed to control a valve which in turn controls the 15 admission of fluid to a vessel or the admission of a motive fluid such as steam to a pump for pumping water into a vessel, the height of the contents of the vessel regulating the position of the float.

20 One important object of the invention is to improve the general construction of devices of this character.

A second important object of the invention is to provide a float controlled water 25 regulator including a valve operatively connected to the float and means to vary the extent of movement of the valve while at the same time maintaining the extent of movement of the float.

30 A third important object of the invention is to not only provide means for varying the extent of movement of the valve but also means for varying the terminal positions of such valve, as for instance the 35 valve may have an extent of movement equal to one-half inch but the points at which this movement begins and ends may be varied at will.

With the above and other objects in view, 40 as will be hereinafter apparent the invention consists in general of certain novel details of construction and combinations of parts hereinafter fully described, and illustrated in the accompanying drawings, and 45 specifically claimed.

In the accompanying drawings, like characters of reference indicate like parts in the several views, and:

Figure 1 is a side elevation of a regulator constructed in accordance with this invention.

Fig. 2 is a vertical median section therethrough.

Fig. 3 is a detail section similar to the valve end of Fig. 2 but showing the valve in 55 a second position.

Fig. 4 is a section on the line 4-4 of Fig. 1.

Fig. 5 is a section on the line 5-5 of Fig. 4. 60

Fig. 6 is a detail section on the line 6-6 of Fig. 1.

In the embodiment of the invention herein illustrated there has been disclosed a casing 10 of the usual bowl shape and this 65 casing is open at the top, the top being closed by a cap 11 secured to the casing by stud bolts 12. At the top of the cap there is provided a pipe connection 13 and a similar pipe connection 14 is provided at the 70 bottom of the casing so that the casing can be connected to a tank or boiler or other like vessel above and below the water line, the normal water line preferably passing through the casing on the section line 6-6 75 of Fig. 1. This casing moreover, has on one side connections 15 so that a gage glass 16 may be carried at the side of the casing and thus enable the operator to visually observe the height of water within the casing. 80

Projecting from one side of this casing is a hollow extension 17 provided with an opening 18 on its underside near its outer end, the opening being faced off at the bottom for purposes hereinafter to be set forth. 85 Extending through one of the side walls of the casing is a pivot pin 19 and pivotally mounted on this pin is an arm 20 which passes between guides 21 at the end of the extension adjacent the body of the casing. 90 Disposed substantially centrally of the casing is a float 22 which is connected to the arm 20 and as this float rises and falls the arm is moved upward and downward in accordance with the movement of the float. 95 The float and arm are preferably so proportioned that the normal water line will pass through the center of the float when the arm is horizontal.

Covering the opening 18 and seated on 100 the faced off portion of the casing is a plate 23 which is arranged to assume either the

position shown in Figs. 1 and 2 or the position shown in Fig. 3. This plate is secured to the casing by means of suitable bolts 24. Formed on the inner side of the plate is a 5 stuffing box 25 the outer diameter of which is considerably less than the inner diameter of the opening 18 so that this stuffing box, which is eccentric to the plate 23, may be either positioned to the side of the opening 10 close to the end of the extension or to the side of the opening which is remote from the end of the extension. This stuffing box is provided with the usual packing 26 and gland 27. It is to be noted that by this 15 means the stuffing box which is positioned vertically beneath the arm 21 may be caused to assume either of two positions with respect to the pivot of said arm. Through this stuffing box extends a valve stem 28 20 which is connected to one of two openings 29 formed in the arm 20 by means of a suitable pivot bolt 30, the bolt passing through one of these openings when the parts are in the position shown in Fig. 2 and 25 through the other of the openings when the parts are in the position shown in Fig. 3.

The valve comprises a body 31 which has at its lower part the bonnet 32 provided with a pipe connection 33. Moreover, the valve 30 body 31 is provided within the bonnet with a valve seat 34 against which a valve 35 is engageable, the valve 35 being either all of metal or being an elastic disk such as rubber supported in a shell 36. This shell 36 is carried by the lower section 37 of the valve stem, this section passing upward through the valve body and through a stuffing box 38 provided on the body, the stuffing box carrying the usual gland 39. This lower 40 section 37 is connected to the upper section 28 of the valve stem by means of screw threads 40, the lower section being hollow to receive the upper section. Moreover, on this upper section 28 there is provided a jam 45 or lock nut 41 by means of which the upper and lower sections of the valve stem may be locked in adjusted position, the lower section being provided with suitable openings 42 for the purpose of inserting a pin and 50 turning one section with respect to the other. As previously described, the plate 23 permits of adjustment of the valve stem longitudinally of the arm 21 without in any way varying the position of the arm or float and 55 thus the extent of movement of this stem and consequently of the valve can be varied at will.

It will be noted that a plurality of spaced openings 29 are formed in the arm 20 for 60 permitting adjustment of the pivot 30 connecting the valve stem to the arm to vary the movement of the valve, see Fig. 3 of the drawing, the valve stem being lengthened or

shortened by the simple adjustment of the parts 37 with respect to the upper part 28. 65

It will be obvious that a second pipe connection 43 is provided for the body 31.

This valve body is also provided with a base 44 which is secured to the frame or base 45 of the device by means of bolts 46, a facing or liner plate 47 being interposed between the parts 43 and 44 when the valve is in one position as shown in Fig. 2 and this plate being omitted when the valve is in the second position shown in Fig. 3. 70 75

From the foregoing it will be seen that the valve can either be used as a short stroke or a long stroke valve and that the position at full opening can be regulated at will.

There has thus been provided a simple and 80 efficient device of the kind described and for the purpose specified.

It is obvious that many minor changes may be made in the form and construction of the invention without departing from the 85 material principles thereof. It is not therefore desired to confine the invention to the exact form herein shown and described but it is wished to include all such as properly come within the scope claimed. 90 95

Having thus described the invention, what is claimed as new, is:—

1. In a water regulator, a casing, a float in said casing, an arm connected to the float and pivoted in the casing, said casing being 95 provided with an opening vertically disposed with relation to the arm, a cover plate for said opening provided with an eccentric stuffing box, means to secure said plate on said casing over the opening with the stuffing 100 box in the path of movement of the arm, said means being arranged to secure the plate in either of two positions, a valve stem passing through the stuffing box and shiftable therewith, and a valve connected to and 105 controlled by said stem.

2. In a water regulator, a casing, a float in said casing, an arm connected to the float and pivoted in the casing, said casing being provided with an opening vertically disposed with relation to the arm, a cover plate for said opening provided with an eccentric stuffing box, means to secure said plate on said casing over the opening with the stuffing box in the path of movement of the arm, 115 said means being arranged to secure the plate in either of two positions, a valve stem passing through the stuffing box and shiftable therewith, a valve connected to and controlled by said stem, and means to vary the 120 length of said stem.

3. In a water regulator, a float casing having a hollow arm extending therefrom and provided with an opening in its under side, a float in said casing, an arm connected 125 to the float and pivoted in the hollow arm

of said casing for permitting vertical movement of the float, a cover plate adjustably mounted on the hollow arm and having an eccentric stuffing box extended within the opening in said hollow arm and adapted to 5 be positioned at various points therein, valve mechanism arranged below the hollow arm, and a valve rod for controlling said valve mechanism adjustably connected with the

arm of the float and working through the stuffing box.

In testimony whereof I affix my signature 10 in the presence of two witnesses.

WILLIAM H. MINEKIME.
